UNITED STATES PATENT OFFICE.

HISATAKA ICHIKAWA, OF NEW YORK, N. Y.

DESIGN FOR AN ORNAMENT FOR A LAMP-SHADE.

52,891.

Specification for Design.

Patented Jan. 14, 1919.

Application filed November 5, 1918. Serial No. 261,303. Term of patent 3½ years.

To all whom it may concern:

Be it known that I, HISATAKA ICHIKAWA, a subject of the Emperor of Japan, residing in New York, county of New York, and State of New York, have invented and produced a new, original, and ornamental Design for an Ornament for a Lamp-Shade or Similar Article of Manufacture, of which the following is a specification, reference being had to the accompanying drawing, forming a part thereof.

The drawing shows a perspective view of the ornament for lamp shade.

I claim:—

The design for an ornament for a lamp shade, as shown.

In testimony whereof I hereunto affix my signature.

HISATAKA ICHIKAWA.
